UNITED STATES PATENT OFFICE

EMMA FLORA BARRON, OF ASHLAND, PENNSYLVANIA

INDICATING OR ORDER CARD

Application filed December 18, 1930. Serial No. 503,298.

This invention relates to improvements in indicating devices and pertains particularly to a device designed for the purpose of notifying a tradesman as to the amount of a commodity to be delivered.

The primary object of the present invention is to provide a device to be used particularly for ordering milk and cream, wherein means is provided for indicating the desired amount of milk or cream wanted and wherein certain elements may be shifted to a predetermined position for the purpose of notifying the milk man that no milk or cream is desired.

Still another object of the invention is to provide an indicator card so designed that an extra card may be mounted thereon to carry information for the milk man, not forming a permanent part of the indicia on the card.

The invention will be best understood from a consideration of the following detailed description taken in connection with the accompanying drawings forming part of this specification, with the understanding, however, that the invention is not confined to any strict conformity with the showing of the drawing but may be changed or modified so long as such changes or modifications mark no material departure from the salient features of the invention as expressed in the appended claims.

In the drawings:

Figure 1 is a view in front elevation of the indicator embodying the present invention.

Figure 2 is a sectional view taken on the line 2—2 of Figure 1.

Figure 3 is a sectional view taken on the line 3—3 of Figure 1.

Referring more particularly to the drawings, wherein like numerals of reference indicate corresponding parts throughout the several views, the numeral 1 indicates a card which may be of any appropriate material, cardboard being preferred as the device may be economically produced by using this material. The card 1 is provided at its upper end with an aperture 2 by means of which it may be hung up in posi-

tion or, if preferred, any suitable means may be provided whereby the card may be made to stand upright. The face of the card is divided into two vertically arranged groups of spaces disposed in spaced relation upon opposite sides of the longitudinal center of the card, the spaces upon one side being indicated by the numerals 3 and having the notation "milk" 4 at the top thereof while the spaces upon the other side, which are indicated by the numerals 5, have the notation "cream", as indicated at 6, at the top thereof. 55

Beneath the word "cream" is printed "pint", as indicated at 7, and beneath the word "milk" is printed "quart" and in the columns beneath these words are figures indicating different amounts as, for example, in the cream column there are the figures $1\frac{1}{2}$, "1", $1\frac{1}{2}$ and "2" and in the milk column there are the figures $1\frac{1}{2}$, "1", "2" and "3". 60

The vertical columns of spaces 3 and 5 are enclosed in an area defined by the border lines 9 and at the top of this area between the upper ones of the spaces 3 and 5 there is provided the central space 10 in which, at one side, is printed in large letters the word "no" and at the opposite side, in smaller letters and one above the other, the words "cream" and "milk". At the bottom of the area defined by the lines 9 is a pair of spaced vertically arranged slits 11, the purpose of which will be hereinafter described. 75

In the central portion of the area in which the spaces 3, 5 and 10 lie there is pivotally mounted upon a button 12, which passes through the body of the card, the two hands 13. These hands are held sufficiently tight between the enlarged ends of the button to cause them to retain any position to which they may be shifted. 80

The top of the card 1 above the area defined by the lines 9 may bear the caption "milk", as shown, or any other legend desired and the portion of the card below this area may be employed for advertising purposes. 85

In the use of the present device, if both 100

milk and cream are desired, notice of this fact may be given the milk man by arranging the hands 13 in the manner indicated so that one of the hands may point to $\frac{1}{2}$, 1, 5 etc., on the cream side, indicating the desire for $\frac{1}{2}$ or 1 pint of cream and the other hand may be arranged to point to any of the figures selected to indicate the number of quarts of milk or fraction thereof desired.

10 If only milk and no cream is desired then one of the hands may be directed toward the proper figure in the milk column, while the other may be directed toward the space 10 in which the words "no cream-milk" is 15 printed so that the delivery man will understand that as milk has been ordered cream is not wanted. It will, of course, be apparent that if neither milk nor cream is wanted than both hands may be directed 20 toward the words in the space 10.

If an amount of cream or milk greater than the amounts indicated on the card is wanted then the desired amount may be printed upon a slip of paper, such as is indicated in Figure 3 by the numeral 14, and the ends of this slip may be inserted in the 25 slots 11 of the card so that the slip will be held in position across the central lower portion of the area 9, as shown in dotted lines 30 in Figure 1.

If the order is for additional milk the amount wanted may be printed upon the right hand side so as to be closest to the column of spaces under the word "milk" and 35 one of the hands may then be arranged to indicate the figure upon the slip.

From the foregoing it will be readily appreciated that with an indicator of the character herein described instructions may be 40 easily and clearly given to a milk man or to persons delivering other commodities, in which case, as will be readily understood, the terms upon the card indicating the articles wanted will be changed.

45 Having thus described my invention, what I claim is:

1. An indicator of the character described, comprising a card having thereon two columns of figures indicating quantities 50 of a commodity to be ordered, and a selected commodity name printed at the head of each of said columns, a pair of indicating hands pivotally mounted between said columns each being designed to indicate a 55 quantity in a column, and means whereby a character bearing slip may be added to the card for indicating a quantity desired different from the quantities indicated in the columns.

60 2. An indicator of the character described, comprising a card, a series of longitudinal and transverse markings on the card dividing the same into two parallel columns of spaces, printed matter heading 65 each of said columns constituting the names

of commodities to be ordered, printed characters beneath said commodity names constituting measures of said commodities, quantity indicating characters arranged in the spaces of each column beneath said measures, and a pair of indicating hands pivotally mounted on the card between said columns and adapted to be shifted to designate a selected one of said numerals, said card having a pair of vertically arranged slits therein each adjacent one of said columns providing means whereby an indicia bearing slip may be attached to the face of the card by inserting one end thereof in each slit.

70 3. An indicator of the character described, comprising a card having thereon two columns of figures indicating quantities of a commodity to be ordered and a selected commodity name printed at the head of each of said columns, a pair of indicating hands pivotally mounted between said columns each being designed to indicate a quantity in a column, and means whereby a character bearing slip may be added to the card for indicating a quantity desired 75 different from the quantities indicated in the columns, said means being located in close proximity to said hands whereby said hands may be arranged adjacent and to indicate a character placed on the slip.

80 In testimony whereof I hereunto affix my signature.

E. FLORA BARRON.
